FIG. 3

FIG. 4

To all whom it may concern:

Be it known that we, Herman J. Troche and Peter Licursi, have invented a new, original, and ornamental Design for an Aerial Ladder for Trucks, of which the following is a specification, reference being had to the accompanying drawings, forming a part hereof.

Fig. 1 is a left side and rear perspective view of an aerial ladder for trucks showing our new design with the ladder in storage or traveling position;

Fig. 2 is a rear elevational view of Fig. 1;

Fig. 3 is a perspective view thereof on a reduced scale with the aerial ladder in fully elevated position; and

Fig. 4 is another perspective view thereof shown in reduced scale with the aerial ladder in another position.

The truck disclosed by means of broken lines on the drawings is shown for illustrative purposes only.

We claim:

The ornamental design for an aerial ladder for trucks, substantially as shown and described.
